HIS ATTORNEY

Patented Nov. 27, 1923.

UNITED STATES PATENT OFFICE.

PHILMORE F. SPERY, OF CHICAGO, ILLINOIS.

RADIATOR CORE.

Application filed January 16, 1922. Serial No. 529,701.

To all whom it may concern:

Be it known that I, PHILMORE F. SPERY, a citizen of the United States, residing at Chicago, in the county of Cook and State of Illinois, have invented new and useful Improvements in Radiator Cores, of which the following is a specification.

This invention has relation to a radiator for an internal combustion engine of the water cooled type, and it refers particularly to the core construction of such radiator.

The object of my invention is the provision of means for increasing the cooling capacity of the radiator. A further object is to provide a simple, durable and inexpensive structure of the type mentioned. With these objects in view my invention consists in the novel combinations and important features hereinafter fully explained and illustrated in the appended drawing, of which:

Fig. 1 is a fragmentary front elevation of a radiator core embodying the invention.

Fig. 2 illustrates a subdivision of Fig. 1, one of the composite members of the core.

Fig. 3 is a fragmentary side elevation of the structure shown in Fig. 2.

Fig. 4 is a cross sectional end view of Fig. 3, taken substantially on line 4—4.

Fig. 5 is a cross sectional elevation of one of the water channels of the core.

Fig. 6 shows the water channel, and is taken on a line 6—6 of Fig. 5, and

Figs. 7, 8 and 9 illustrate a portion of a spacing structure mounted within each of the members shown in Fig. 2.

As viewed from the front or the rear the radiator core is of a hexagonal cellular type, and it is noticed that the passage through the cells is more or less obstructed by series of peaked projections formed by the insertion of the spacing members of Figs. 7, 8, 9, the purpose of which will appear presently. The water channels are produced by assembling side by side a plurality of the frames of Fig. 2. Each of said frames comprises a pair of corrugated strips 1 and 2, which strips may be exactly alike in general outline, but are placed relatively end for end, whereby each top surface 1^a of one strip is positioned opposite the bottom surface 2^b of the other. The strips 1 and 2 are suitably combined at the top and bottom by lock seams 3 and 4. Now it is noticed, by referring to Figs. 3 and 4 that the strip 1, and similarly the strip 2, is a thin piece of metal

from the bottom of which, 1^b, rises uniformly spaced indentations terminating in the top surfaces 1^a. Along the edges it is seen that these indentations are much enlarged, so as to form the semihexagonal bands 1^c, 1^d (and 2^c, 2^d). In the bottom surface of the strip is provided, adjacent to said band indentations, two series of semi-spherical protuberances 1^e, 1^f.

As hereinbefore mentioned I place a spacing member 5 within each water channel frame 1, 2, and it is noticed that this spacing member 5 is made with semihexagonal bands along its side edges, the oppositely directed top surfaces of which, indicated by the numerals 5^a, 5^b, are caused to abut the bottom surfaces 1^b, 2^b of the water channel frames, thereby completing the hexagonal cellular structure. The middle portion of the strip 5 is formed to present a similar semihexagonal band, but it is noticed that the corrugations 5^c are in reversed relation to the side corrugations 5^a, 5^b. Intermediate this middle band and the two edge bands is found a pair of narrow bands, the metal of which is formed into a finer saw tooth shape, there being about three teeth to each hexagonal corrugation. The reason for, and purpose of this construction is twofold. In the first place it would not be commercially possible to roll or stamp the strip into the shape of the three major bands in the manner shown, because the metal would be torn to pieces. But assuming the shape to have been produced, the result would be that the relatively opposite corrugations of the middle band would be placed directly behind the corrugations of the edge bands and that they would block the air passages through the outer corrugations, and thereby prevent the air from flowing through the core.

In the structure presented the air entering from the front through a corrugation 5^b first strikes a tooth 5^d with the result that it is deflected or spread around and past said tooth and around the peak 5^c of the aligned middle corrugation. The air then glides along the beveled surfaces 5^a, 5^b, finally to strike the teeth 5^e, whereupon it again is deflected upward and downward, around the corrugations of the rear band. An examination of the structure of Fig. 5, in connection with the foregoing description, will show that the air passing through the core, and being split up and variously directed, will strike the sides of the water

channels with great force. Take, for example, the air entering along the three pointed arrow C. This air will first strike the tooth 5^e, then slide off and strike all three sides of the water channel corrugation.

It is well known that, the more thoroughly the air can be cut up, deflected in various directions and thrown against the water channel sides, the more complete will be the cooling operation also. In the foregoing I have presented a very efficient structure, and I have also succeeded in solving a very difficult problem, that namely of devising a way of equalizing the strain on the metal 15 incident to the operation of forming the strip into the shape shown.

In order to maintain the water channels in alignment with the spacers during the operation of assembling the core and prior 20 to the usual soldering operation, I have provided two series of buttons, 5^a, 5^b, extruded from the metal of the spacers, and these buttons fit within the protuberances 1^e, 1^f of the water channel sides.

25 I claim:

1. In a radiator core, the combination with a series of corrugated water channels, of a similarly corrugated spacer fixed between each pair of water channels, said 30 spacer made with a pair of edge bands and a center band, all three of which are of the same shape but the corrugations of the center band are reversed relative to those of the edge bands, there being more finely corrugated bands intermediate said center and edge bands.

2. In a radiator core, the combination with semihexagonal water channels, of a spacer mounted between each pair of channels, said spacer having similar semihexagonal edge bands and middle band, the latter in reverse relation to the former, and made with a pair of finer toothed bands intermediate the said three bands.

45 3. In combination, water channels and

spacers, all having semihexagonal edge bands combining to form a hexagonal cellular core; each spacer having a reversed semihexagonal middle band and having narrow strips of saw tooth shape between the 50 center band and the said edge bands.

4. In a radiator core, a series of vertically disposed rectangular frames, the sides of each frame being of semihexagonal contour and made right and left, whereby the right 55 side of one frame forms a water channel with the left side of the next following frame and a spacer occupying the space within each frame, said spacer having semihexagonal edge bands the vertical surfaces 60 of which abut the vertical surfaces of said sides, the spacer having a similar middle band in reverse relation and made with saw tooth bands intermediate the middle and the edge bands.

5. In a radiator core, rectangular frames having vertically disposed semihexagonal sides, spacers mountable within the frames and having edge bands combining with said sides to form a hexagonally cellular core, 70 said spacers having a semihexagonal middle band in reversed relation to the edge bands, there being finely corrugated portions permitting the metal to be drawn into the reverse relation aforesaid, the abutting surfaces of the spacers and the frame sides provided with interfitting aligning bosses.

6. In a radiator core, a spacer made from a thin strip of metal divided into three substantially equal bands of hexagonal outline, except that the center band is formed in reverse relation, there being two narrow intermediate bands of a finer saw tooth shape, whereby the metal of said intermediate bands is properly distributed in forming.

In testimony wherof I have hereunto affixed my signature.

PHILMORE F. SPERY.
